UNITED STATES PATENT OFFICE.

ADOLF SCHRETER, OF BALTIMORE, MARYLAND.

MADE-UP BOW TIE.

Application filed August 17, 1922. Serial No. 582,401.

To all whom it may concern:

Be it known that I, ADOLF SCHRETER, a citizen of the United States, residing at the city of Baltimore, in the State of Maryland, have invented certain new and useful Improvements in Made-Up Bow Ties, of which the following is a specification.

This invention relates to that class of neckties which are sold with a made-up bow. 10 This bow is commonly not tied but made up of separate pieces which are secured together to simulate a double bow knot tied in a string tie.

Where these ties are made up of face fabric alone or with a filler of soft material, they are unsatisfactory because the fabric soon curls up and loses its shape and the life of the tie is very short.

Various expedients have been used to prevent the bow losing shape, such as mounting it on a stiff support or shield at the back, or placing a wire frame within the bow. 20 Neither of these methods are satisfactory for the reason that the first mentioned expedient gives the bow a stiff board-like appearance, and the wire frame has the disadvantage that when the wearer faces the wind, the outline of the frame is clearly visible through the fabric, and with the slender soft wire 25 frames commonly used for this purpose the pressure of the wearer's chin upon the bow when the head is lowered tends to permanently bend the bow out of shape, giving the bow an unsightly appearance of which the 30 wearer is usually unaware as the bow is out of his range of vision.

One of the objects of my invention, therefore, is to provide the bow with a support which will permit the bow to yield readily 40 under pressure but to return to its proper shape upon the pressure being removed.

Another object of my invention is to provide a support which will be entirely invisible from any angle at which the tie may 45 be viewed.

Another object of my invention is to provide a resilient support which will give slightly under its own weight when the wearer bends forward, but return to its previous position upon the wearer returning to 50 erect posture.

Another object of my invention is to provide individual resilient supports for the front and back loops of the bow, these supports differing in material so that one is 55 more readily flexed than the other, giving a

natural movement to the bow when pressure is applied to it.

My invention is capable of embodiment in a variety of forms within the spirit of the 60 claims forming part hereof, one of which is shown in the accompanying drawings.

In the drawings:

Figure 1 is a front elevation of a necktie bow. 65

Figure 2 is a section on line 2—2 of Figure 1.

Figure 3 is a section of the center part of the bow on line 3—3 of Figure 1.

Figure 4 is a perspective view of a bow former. 70

In the drawing, 1 is a loop, formed of an elongated rectangular strip of face fabric with the long edges thereof turned inward as shown at 4 and 5 to form a strip of flattened G-shaped cross section, the ends of the strip 8 and 9 being folded inward to form the loop. 75

2 is a similar loop superimposed upon the loop 1, but facing in the reverse direction, 80 with its edges 6 and 7 turned inward and its ends 10 and 11 folded inward as are similar parts of the loop 1.

3 is a yoke or ring of face fabric which encircles the loops at their center and contracts the loops at that point, thus giving them the form of the conventional bow tie. 85

12 and 13 are formers of resilient material, similar in general outline but preferably 90 differing in thickness or character of material, these formers having the general outline which it is desired to give to the bow. The preferable form has wide flaring edges 14 and 15 and a contracted center portion 95 16, the edges of this center portion being preferably parallel for reasons which will appear hereafter in connection with my description of my method of making the bow.

To make the bow, I cut from some resilient material two formers of the shape shown in Figure 4. These formers may be of any resilient material which will hold its shape. I have found by experiment that resilient fibrous materials are best suited for this 105 purpose, and find as the most satisfactory materials which I have used, rubber fabric, that is woven cotton fabric impregnated with rubber, and thin leather. While these formers may be alike, I have found it desirable to make the former of the rear bow either thicker or of a different material from 110

that used in the front bow, and I commonly use a back former of rubber fabric and a front former of thin leather. A single former may be used but the result is not as satisfactory as a former for each loop.

I provide two elongated rectangular strips of face fabric, approximately twice as long and wider than the desired dimensions of the bow, one to form the front loop and one the back loop.

Taking one of these strips, I bend over the edges throughout their whole length, creasing them to maintain them in their bent over position by pressing with a hot iron. I then insert near the center, one of the formers, placing it under the bent over edges of the fabric, as shown at 4 and 5 in Figure 3. As an alternative construction, the strip of face fabric may be formed into a tube by sewing its edges together and the former pushed in through the end of the tube. I then fold over the ends of the fabric strip which project beyond the former, as shown at 8 and 9 in Figure 2. The former is thus incased somewhat loosely in the face fabric, which forms a loop as plainly shown in Figure 2.

The second former is incased in face fabric in a similar manner to form the second loop and the two loops are then placed back to back, that is in opposite directions, and tightly bound together at the center by a strip of face material forming the yoke 3. The yoke 3 bears against the parallel sides of the contracted center 16 of the formers and is held in this position by the flaring sides of the wings 14 and 15 of the formers.

As heretofore mentioned, I prefer to make the former of the rear bow of rubber fabric

and the front former of thin leather. The formers being narrow and bound in tightly at the center have a tendency to droop slightly at the ends, the leather former being more flexible drooping slightly more than the back rubber fabric former, thus giving a slight irregularity in the form of the bow which is characteristic of hand tied bows and avoiding the stiff board like form which is the common appearance of made-up bow ties.

What I claim is:

1. A necktie bow or the like comprising a plurality of superimposed loops of fabric secured together, each loop provided with a former of resilient sheet material with contracted center portion and outwardly flaring ends infolded within said loop.

2. A necktie bow and the like comprising a plurality of superimposed loops of fabric secured together, each loop provided with a former of resilient, fibrous sheet material with contracted center portion and outwardly flaring ends infolded within said loop.

3. In a necktie bow, a pair of superimposed loops, said loops consisting of lengths of face fabric with edges turned inward to form strips of flattened C-shaped cross sections, resilient formers, of sheet material of the general outline of the bow inserted in the loops between the face fabric and its inturned edges, the outer ends of said strips of face fabric being folded inward to form the loops, and a yoke encircling the center portion of the bow and binding the loops and formers together.

In testimony whereof I affix my signature.
ADOLF SCHRETER.
